UNITED STATES PATENT OFFICE.

VIVIAN A. DEBERTSHAUSER, OF BOWLING GREEN, MISSOURI.

SCREEN.

1,244,841.

Specification of Letters Patent. Patented Oct. 30, 1917.

Application filed September 14, 1914. Serial No. 861,643.

To all whom it may concern:

Be it known that I, VIVIAN A. DEBERTSHAUSER, a citizen of the United States, residing at Bowling Green, in the county of 5 Pike and State of Missouri, have invented certain new and useful Improvements in Screens, of which the following is a specification.

This invention relates to window screens, 10 one of the objects being to provide a screen adaptable for use in windows of various sizes.

Another object of the invention is to provide a durable and efficient screen capable 15 of manipulation in either a vertical or horizontal plane, consistent with its positioning in the window frame, in the present instance being shown as operating in a vertical plane, for the sake of illustration, it 20 being understood that by merely turning the screen in the frame, so as to dispose the longitudinal axis of the screen at right angles to the window sill, that it may be operated in a horizontal plane.

Other objects as well as the nature, characteristic features and scope of my invention will be more readily understood from the following description taken in connection with the accompanying drawings and 30 pointed out in the claim forming a part of this specification.

Referring to the drawings:

Figure 1 is a front elevation of a screen constructed in accordance with my invention, 35 illustrating the application thereof, a portion of the screen being broken away to disclose details, and

Fig. 2 is a sectional view taken on the line 2—2 of Fig. 1.

In the drawings wherein is illustrated the preferred embodiment of this invention in order to illustrate the application thereof, a window casing 5 is provided in which is mounted my improved screen generally 40 designated 6, the latter in the present instance comprising an upper and lower section numbered 7 and 8, respectively. The upper section 7 in the present instance, comprises the usual screening 9, the upper marginal edge of which is engaged with a portion 45 of a sash 10, while the sides and lower marginal edges of the screen are engaged by a metallic strap 11, the portion which engages the lower marginal edge of the 50 screen, being bent upon itself and turned at right angles to the body, as indicated at

12 and shown to advantage in Fig. 2, so as to positively prevent the entrance of flies between the screen sections. As likewise shown to advantage in Fig. 2, the strap 11 60 which engages the sides of the screening 9 slides in a groove 13 formed in the lower screen section 8, while parallel rods 14 depend from the sash 10, each being equipped with a head 15 on its lower end, as shown to 65 advantage in Fig. 1.

The lower section in the present instance comprises an ordinary screen frame 16 upon which screening 17 is retained by a clamping member 18 which is likewise preferably 70 made of wood. The sides of the frame 16 are provided with longitudinally extending elongated openings 19 therein, in which are seated coil springs 20, the latter engaging with the head 15 of the rods 14, so as to 75 normally hold the upper section 7 of the screen snugly in engagement with the casing 5. Guide-strips, as indicated at 21, are counter-sunk in the upper face of the lower section 8 and are provided with openings 80 therethrough alining with the openings 19 in the sides of the section 8 through which the rods 14 engage.

In operation, we will assume that the device is in the position as shown in Fig. 1. 85 In this position, when it is desired to raise the screen, pressure is exerted on the lower section 17, so as to cause the coil springs 20 to be compressed, thereby automatically closing the lower section when pressure is 90 released therefrom. Of course when the screen is mounted in exceptionally small window casings, the springs 20 will normally be under considerable tension so that it will be impossible to raise the lower section 95 to any great extent, but in the standard sizes of windows, considerable play of the lower section will be permitted in order to open communication therebeneath, it being of course obvious that if desired, various 100 sizes of screen may be used, so as to be accommodated in window casings varying in size, but it is one of the principal objects of this invention to provide a window screen which is adaptable for use in connection 105 with windows of various standard sizes. The entire screen may be readily disengaged from the window casing at the option of the user.

It will be understood that the above description and accompanying drawings comprehend only the general and preferred em-

bodiment of my invention and that various minor changes in details of construction, proportion and arrangement of parts may be made within the scope of the appended 5 claim and without sacrificing any of the advantages of my invention.

Having thus fully described my invention, what I claim as new and desire to secure by Letters Patent is:

10. A window screen section including independent perforate screen sections, each of which rigidly engages two parallel sides of the window casing and yieldingly engages the other two parallel sides of the casing,

springs mounted in the ends of one section, 15 headed rods carried by the other section and coacting with said springs to normally force said sections apart, plates countersunk in the spring carrying sections to prevent displacement of the springs and acting as 20 guides for said rods.

In testimony whereof I affix my signature in presence of two witnesses.

VIVIAN A. DEBERTSHAUSER.

Witnesses:

M. O. BIGGS,
E. E. EVANS.
